UNITED STATES PATENT OFFICE.

GUSTAV HOLTZ, OF GOULDSBORO, PENNSYLVANIA.

DESIGN FOR AN AMALGAM CARRIER AND PLUGGER.

57,434.

Specification for Design.

Patented Mar. 29, 1921.

Application filed March 5, 1920. Serial No. 363,569. Term of patent 14 years.

To all whom it may concern:

Be it known that I, GUSTAV HOLTZ, a citizen of the United States, residing at Gouldsboro, in the county of Wayne and State of Pennsylvania, have invented a new, original, and ornamental Design for an Amalgam Carrier and Plugger, of which the following is a specification, reference being had to the accompanying drawing, forming part thereof.

The single figure is a side elevation of an amalgam carrier and plugger, showing my new design.

I claim:—

The ornamental design for an amalgam carrier and plugger, substantially as shown.

In testimony, that I claim the foregoing as my own, I have hereto affixed my signature.

GUSTAV HOLTZ.
